UNITED STATES PATENT OFFICE.

HENRY A. DUC, JR., OF CHARLESTON, SOUTH CAROLINA.

STEAM-BOILER.

SPECIFICATION forming part of Letters Patent No. 707,216, dated August 19, 1902.

Application filed September 3, 1901. Serial No. 74,149. (No model.)

To all whom it may concern:

Be it known that I, HENRY A. DUC, Jr., of Charleston, in the county of Charleston and State of South Carolina, have invented certain new and useful Improvements in Steam-Boilers; and I hereby declare that the following is a full, clear, and exact description thereof, reference being had to the accompanying drawings, which form part of this specification.

This invention is an improvement in furnaces for burning fine or pulverized and liquid fuels and gases, and it has particular reference to boiler-furnaces of the internal-fire-chamber type; and its object is to produce a rapid continuous gyration or circulation of the combustible gases in the furnace during the oxidation thereof, so that the burning gases will sweep over and around all the interior walls of the furnace, applying heat to every portion thereof, thus obtaining the utmost efficiency and economy in fuel and at the same time permitting a utilization of the space ordinarily occupied by grates, bridge-walls, and ash-chambers as part of the active heating-chamber, thereby obtaining in a given-sized boiler-furnace a greater amount of actual heating-surface than is possible in the ordinary furnace construction.

The invention is particularly well adapted to marine and locomotive boilers as well as stationary boilers using cylindrical furnaces, and is especially useful where oils are used as fuel.

The accompanying drawings illustrate the invention, showing various modifications of apparatus capable of use in connection therewith, and the following description thereof will impart a clear understanding of the invention, the essential features wherein the invention consists being summarized in the claims following the description.

In said drawings, Figure 1 is a longitudinal vertical section through a stationary boiler, showing one form of feeding apparatus. Fig. 2 is a similar section through a locomotive-boiler furnace, showing a preferred form of interior construction. Fig. 3 is an end view of Fig. 1, partly in section. Fig. 4 is a detail transverse section of one of the perforated channeled fire-bricks in Fig. 2. Fig. 5 is a

detail view of a modified form of fuel-injecting head. Fig. 6 is a detail.

A designates a boiler, within which is secured a corrugated furnace B. The boiler 55 may be of any suitable form; but the furnace B is cylindrical and annularly or spirally corrugated and is steam-tightly united at its ends to the heads of the boiler, through which the furnace opens.

The fuel (which may be pulverized coal, coke, &c., or hydrocarbon oils or mixtures thereof) is introduced into the feed end of the furnace through a pipe C, this end of the furnace being otherwise suitably closed by a door or cover A'. Pipe C communicates with a hopper C', into which the fuel is fed, and the latter may be forcibly impelled into the furnace by a forced draft caused by the fan or motor D, which may be of any suitable 70 construction. The inner end of pipe C connects with a head or chamber, which is arranged to direct the incoming fuel and air tangentially or spirally outward and against the inner walls of the furnace, thereby causing the currents of fuel to gyrate and rotate circumferentially therein, as indicated by arrows, this gyration being increased by the expansion of gases caused by ignition and oxidation thereof. The particular form of the 75 head or chamber may be varied, and I have indicated several forms in the drawings. In Figs. 1 and 3 three radiating curved arms E are connected to the inner end of pipe C, and through these the fuel-gases, &c., are projected tangentially against the inner walls of the furnace B. In Fig. 5 a cluster of curved injecting-pipes E' are connected to the inner end of pipe C. In Figs. 2 and 4 a channeled hollow cylindrical fire-brick chamber is shown, 90 which is of less exterior diameter than the internal diameter of the furnace and is composed of a series of bricks centered in the furnace by means of exterior spirally-inclined lugs or projections F', and said bricks are 95 provided with a series of circumferential and tangential jet-passages f, through which the gases are ejected with great violence against the internal wall of the boiler B. I prefer, particularly when the invention is adapted for 100 locomotive-boilers, to employ this fire-brick chamber F within the furnace, as indicated

in Fig. 2, and preferably the inner wall of this chamber F is also annularly corrugated, as shown at F² in Fig. 2, which will assist in causing the gases to pass through the jet-
5 openings f into the annular space G between the outer walls of the chamber F and the inner wall of the furnace B.

To assist in mixing and imparting violent eddying or gyrations to the fuel, spiral deflectors c may be placed in the inner end of feed-pipe C, as indicated in Fig. 6. The inner end of the cylindrical chamber F is closed by a fire-brick end piece f', as indicated in Fig. 2, so that the gases must pass 10 out through the openings f and against the walls of furnace B. The gases escape eventually from furnace B into breeching J, thence back through the tubes a to stack K. On a locomotive they would pass from the cinder-
15 box to the stack as usual.

Operation: The fuel is injected into the furnace in such manner that the burning gases are caused to rotate or gyrate circumferentially therein, their longitudinal passage 20 therethrough being retarded both by their gyrating motion and by the corrugations of the furnace, which corrugations form detaining channels or traps, in which the gases travel, and by their rapid rotary movement 25 30 the burning gases sweep around the furnace, contacting with and imparting heat to the entire walls thereof and being thrown and held in contact therewith by their centrifugal action. The velocity of the gyrating currents of burning gases depends, of course, 35 upon the force with which the fuel is injected into the furnace, and their injection may be caused by propulsion of gases by pumps or motors D or by suction from the outlet end 40 of furnace, which suction may be caused, like ordinary natural draft, by the height of stack, or, on locomotives, by the exhaust, or both forced injection and suction may be used to produce the desired violent gyration of the 45 burning gases. Nograte being used, the gases can come directly into contact with every portion—top, sides, and bottom—of the interior walls of the cylindrical furnace, and the natural tendency of the hot gases to collect at the 50 top of the furnace is prevented by the forced circumferential gyrations of the gaseous currents, so that heat is applied to all portions of the furnace practically uniformly, and all parts of the surface of the furnace are utilized 55 as heating-surfaces. Where the cylindrical fire-brick chamber F is employed, it causes a thorough commingling of the gases in the internal chamber H. Then these gases pass in tangential jets into the exterior annular chamber G, wherein they circulate circumferentially around the bricks and against the inner walls of the furnace, thoroughly heating 60 every part thereof, and the bricks F², becoming intensely heated, constitute a large body 65 of highly-heated matter within the furnace, which will assist in heating the walls thereof by radiation and convection and also facil-
70

tate and insure the vaporization of the fuel and thorough oxidation of the gases passing therethrough.

Another advantage of the invention resides in the tendency of the gyrating gases to delay the longitudinal flow of the heat caused by the exhaust, thereby giving more time for the transmission of heat into the boiler. The 75 corrugations also will retard endward advancement and premature escape of the burning gases.

The valuable feature of causing a circumferential gyration or whirling of the gases 80 along, around, and within the annular internal furnace is of great practical value, and this important feature of the invention can be obviously realized by various modifications of the fuel-feeding means, and therefore 85 I do not wish to confine myself to the particular constructions shown, except where specifically mentioned in the claims.

Having thus described my invention, what I therefore claim as new, and desire to secure 90 by Letters Patent thereon, is—

1. The combination of an internal cylindrical furnace, an annular fire-brick chamber therein having tangentially-arranged passages for the escape of the gases, and means 95 for introducing fuel into said chamber, substantially as and for the purpose described.

2. In a furnace, the combination of a cylindrical internally-corrugated fire-chamber, and a jet-head located within the fire-chamber 100 through which the fuel is introduced thereto, said head causing the burning gases to gyrate in the fire-chamber, substantially as and for the purpose set forth.

3. The combination of the boiler, a cylindrical internally-corrugated furnace arranged within the same, a jet-head located within the furnace for causing the burning gases to gyrate violently within said furnace and against the walls thereof, and means for feeding fine 105 fuel to the jet-head, substantially as set forth.

4. The combination of the boiler, a cylindrical internally and annularly corrugated furnace arranged within the same, a jet-head located within the furnace for causing the 110 burning gases to gyrate violently within and circumferentially of said furnace and against the walls thereof, and means for feeding fine fuel to the jet-head, substantially as and for the purpose set forth.

5. In a boiler-furnace, the combination of a boiler, a cylindrical furnace therein, and a cylindrical fire-brick chamber within said furnace provided with tangentially-disposed openings for the escape of gases whereby the 115 latter are caused to circulate circumferentially within the furnace, substantially as and for the purpose set forth.

6. The combination of a boiler, a corrugated cylindrical furnace therein, a cylindrical fire-brick chamber within said furnace provided with a series of tangentially-disposed openings for the escape of gases, whereby the latter are directed against the inner wall of the 130

furnace and caused to circulate circumferentially within the furnace and around said fire-brick chamber, substantially as and for the purpose described.

5 7. In a boiler-furnace, the combination of a boiler, a cylindrical furnace therein, a cylindrical fire-brick chamber within the furnace composed of a series of annular fire-bricks having tangential gas-passages, and means for feeding fuel into said chamber, the gases jetted from said chamber being caused to gyrate in the annular space between the outer walls of said chamber and the inner wall of the furnace, substantially as described.

10 8. In a boiler-furnace, the combination of a boiler, an internal circumferentially-corru-gated cylindrical furnace, a cylindrical fire-

brick chamber within the furnace, said chamber being composed of a series of annular fire-bricks having tangential fuel-passages, and provided with external lugs spacing them from the walls of the furnace, and means for feeding fuel into said chamber, the gases jetted from said chamber being caused to gyrate in the annular space between the outer walls of said chamber and the inner wall of the furnace, substantially as and for the purpose set forth.

15 In testimony that I claim the foregoing as my own I affix my signature in presence of two witnesses.

HENRY A. DUC, JR.

In presence of—

JAMES R. MANSFIELD,
ARTHUR E. DOWELL.
